UNITED STATES PATENT OFFICE.

NICHOLAS CAIN, OF DETROIT, MICHIGAN.

PROPELLER-WHEEL.

SPECIFICATION forming part of Letters Patent No. 310,789, dated January 13, 1885.

Application filed October 11, 1884. (No model.)

To all whom it may concern:

Be it known that I, NICHOLAS CAIN, of Detroit, county of Wayne, State of Michigan, have invented a new and useful Improvement 5 in Propeller-Wheels; and I declare the following to be a full, clear, and exact description of the invention, such as will enable others skilled in the art to which it pertains to make and use it, reference being had to the accompanying 10 drawings, which form a part of this specification.

My invention relates to an improvement in propeller-wheels, as hereinafter specified, and more particularly pointed out in the claims.

15 In the drawings, Figure 1 is an end view, and Fig. 2 a side view, of a propeller-wheel embodying my invention. Fig. 3 is a side view with the wheel revolved ninety degrees from the position shown in Fig. 2. Fig. 4 is 20 a view of the opposite end from that shown in Fig. 1.

Heretofore propeller-wheels have generally been made with two, three, or four blades, the plane of each blade arranged at an angle with 25 the axis of the shaft corresponding with any desired degree of pitch. Such devices, however, have been found to so agitate and beat up the water in which the wheel is turning that the wheel fails to profit by all the resistance 30 which the water would otherwise afford.

It is the object of my invention to produce an improved form of wheel, which, with a given diameter, will utilize to a much larger extent the resistance of the water. I accomplish this as follows: A represents the hub; B, the blades. The blades are two in number. Each blade is made to nearly or quite encircle the hub, as shown in Fig. 2. It extends from b and ends at b', and the depth of 40 the blade is measured in the direction of the axis—viz., the distance b b' is nearly as great as the distance between planes bounding the extreme front and rear of the wheel.

The cutting or leading edges b² are arranged 45 substantially as shown in Fig. 4, and I prefer, in bringing them to an edge, to bevel away the material from the rear instead of from the front of the blade.

I have discovered by practical use of this 50 wheel that water intercepted or cut by one of the blades B is not splashed and broken to the extent usual with propeller-wheels, but is

driven directly back of the wheel, and that when it passes beyond the rear edge, b³, of the blade it is not permitted to eddy around in front of the blade, because the leading edge of the other blade has already passed in advance of the said discharging water. The construction is, moreover, such adjacent to the hub that the water is not here beaten and splashed; 60 but the leading edges cut the water naturally and throw it to the rear along an unbroken and natural channel formed between the two blades. It is thus seen that little or none of the driving-power is wasted by this beating 65 and splashing process, which always represents a resistance to the propelling effect of the power. I have always found by experience with the wheel that with the same exercise of power a wheel like mine of a given 70 diameter effects a considerably greater propulsion of the boat than is effected by one of the propeller-wheels of the usual construction. The rear edges of the blades are indicated by b³ in Fig. 4. These edges also incline slightly 75 forward as they approach the hub, as shown in Fig. 4. This construction assists a natural discharge of the water adjacent to and along the line of the shaft, and obviates in a considerable degree the tendency of the water to discharge by centrifugal action from the periphery of the blade. It will be seen that while the cutting-edges b² are nearly straight the rear edges, b³, curve from the point of each blade through substantially about one-third 80 of the circle described from the axis A, and then curve inward toward the axis, causing each blade to somewhat resemble in projection an ellipse.

Having thus described my invention, what I claim is—

1. A propeller-wheel having two blades mounted spirally upon an axis which is entirely embraced by each, the leading edges of each blade being nearly straight and the rear edges curved and inclined slightly forward as they approach the axis, substantially as described.

2. A propeller-wheel having its leading edges b² slightly curved and its rear edges, b³, curved from the point of each blade substantially in the arc of about one-third the circle described from the axis A, and then curved inward to the axis, the blades being spirally

mounted on said axis and entirely or nearly embracing it, substantially as described.

3. The propeller-wheel having two blades, B B, spirally mounted on a hub, A, and entirely or nearly entirely embracing it, said blades having leading edges b^2 , which are nearly straight or curved but slightly, and rear edges, b^3 , which from the points of the blades are substantially coincident with about one-third

the circle described from the axis, and curved to thence inward, substantially as described.

In testimony whereof I sign this specification in the presence of two witnesses.

NICHOLAS CAIN.
